UNITED STATES PATENT OFFICE.

PHINEAS B. MYERS, OF MORRISTOWN, NEW JERSEY.

DESIGN FOR A PAPER BOX.

SPECIFICATION forming part of Design No. 34,528, dated May 21, 1901.

Application filed April 29, 1901. Serial No. 58,095. Term of patent 7 years.

To all whom it may concern:

Be it known that I, PHINEAS B. MYERS, a citizen of the United States, and a resident of Morristown, Morris county, New Jersey, have 5 invented a new and original Design for Paper Boxes, of which the following is a specification, reference being had to the accompanying drawings, in which—

Figure 1 is a perspective view of a paper box, 10 showing my new design; and Fig. 2 is a vertical section on line 2 2, Fig. 1.

As shown in the drawings, the leading feature of my design consists of a paper box A, upon which is represented a fireplace a, 15 through which appears a picture of Santa

Claus b. Upon the mantel are represented a clock and toys c. Children kneeling upon a bed d look through a window e. A table f and chair g are also shown.

What I claim is—

20 The design for a paper box, substantially as herein shown and described.

Signed by me at New York city, county and State of New York, this 27th day of April, 1901.

PHINEAS B. MYERS.
